UNITED STATES PATENT OFFICE.

GEORGE HOOKHAM, OF BIRMINGHAM, ENGLAND.

ELECTRICITY-METER.

No. 925,187.

Specification of Letters Patent.

Patented June 15, 1909.

Application filed July 18, 1908. Serial No. 444,205.

To all whom it may concern:

Be it known that I, GEORGE HOOKHAM, a subject of the King of Great Britain and Ireland, and residing at Solar Works, New 5 Bartholomew street, Birmingham, in the county of Warwick, England, have invented certain new and useful Improvements in Electricity-Meters, of which the following is a specification.

10 This invention relates to electricity motor meters in which an armature revolves in a mercury bath. In such meters it is customary to seal up the mercury chamber while the meters are in transit to prevent loss of 15 mercury. This is effected by means of a tube surrounding the armature spindle and so arranged that it may be extended tele- 20 scopically until its upper edge bears against a valve seating carried by the armature spindle. In manipulating this valve I have found that the air necessarily included in the 25 extended upper portion of the tube is liable to get transferred to the armature chamber and prevent regular and uniform working of the meter.

The object of the present invention is to overcome this disadvantage.

The invention consists in providing an additional space for mercury forming part of or 30 in connection with the main mercury bath and so arranged that the mercury may be forced out of it as the telescoping tube extends so that the tube is kept always full of 35 mercury until it meets the valve seat forming the seal.

The invention is shown in the accompanying drawings, in which:—

Figure 1 is a vertical sectional view, and Fig. 2 is a central vertical section through 40 the meter.

In Fig. 1 I provide a passage, *a*, in the upper wall of the mercury chamber, *b*. A plunger, *c*, works in the passage *a*, and is connected by a link, *d*, with the outer end of a 45 lever, *e*, pivoted at *f*, the inner end of the lever, *e*, being pivoted to the arm, *g*, pivoted at *i* by which the telescoping tube *h* is raised and lowered. The raising of the arm is effected by the spring, *k*, which holds the 50 arm and the tube, *h*, against the soft washer, *j*, on the armature spindle, *l*. The arm, *g*, is moved downward to free the spindle by means of the rod, *m*, operated by the screw, *n*.

It will be seen that in the above described 55 arrangement, when the telescoping tube, *h*, is

raised the plunger, *c*, is correspondingly lowered into the mercury chamber and the area of the passage, *s*, is such that the mercury displaced from the main mercury chamber is just sufficient to fill the increased space 60 due to the raising of the tube.

If desired, instead of providing a plunger as above described the wall of the additional space may be made collapsible, for instance, the tube *o* might be replaced by a rubber tube 65 which collapses as the tube *h* moves upward.

It will be seen that other forms of seal may be used than that above described.

Having now described my invention what I claim as new and desire to secure by Letters Patent is:—

1. In an electricity motor meter, in combination, a mercury chamber, an armature mounted therein, an auxiliary chamber in communication with said mercury chamber 75 and means for forcing mercury from said auxiliary chamber.

2. In an electricity motor meter, in combination, a mercury chamber, an armature mounted therein, a spindle carrying said armature, an auxiliary chamber in communication with said mercury chamber, means for sealing said mercury chamber, and means for forcing mercury from said auxiliary chamber into said mercury chamber. 80

3. In an electricity motor meter, in combination, a mercury chamber, an armature mounted therein, a spindle carrying said armature, means for lifting said spindle, an auxiliary chamber in communication with 90 said mercury chamber, and means for forcing mercury from said auxiliary chamber when said spindle is lifted.

4. In an electricity motor meter, in combination, a mercury chamber, an armature 95 mounted therein, a spindle carrying said armature, a telescopic tube forming with said spindle a mercury seal, an auxiliary chamber in communication with said mercury chamber, a piston working in said auxiliary chamber, and means actuating said mercury seal and said piston, as and for the purposes described.

In testimony whereof, I affix my signature in presence of two witnesses.

GEORGE HOOKHAM.

Witnesses:

ARTHUR BERNARD FISHER,
WILLIAM WORTON.
